(74) Attorney, Agent, or Firm—Banner & Witcoff, Ltd.

CLAIM

The ornamental design for a portion of a golf club head, as shown and described.

DESCRIPTION

FIG. 1 is a bottom perspective view of a driver head showing my new design;

FIG. 2 is a bottom plan view thereof;

FIG. 3 is a rear view thereof;

FIG. 4 is a toe end view thereof; and,

FIG. 5 is a heel end view thereof.

The broken line showing of the ribs within the claimed regions and the remainder of the golf club head is for illustrative purposes only and forms no part of the claimed design.
